United States Patent Office.

GEORGE W. HEATH, OF BURLINGTON, PENNSYLVANIA.

Letters Patent No. 80,950, dated August 11, 1868.

IMPROVEMENT IN HORSE HAY-FORKS.

The Schedule referred to in these Letters Patent and making part of the same.

TO ALL WHOM IT MAY CONCERN:

Be it known that I, GEORGE W. HEATH, of Burlington, in the county of Bradford, and in the State of Pennsylvania, have invented certain new and useful Improvements in Horse Hay-Forks; and do hereby declare that the following is a full, clear, and exact description thereof, reference being had to the accompanying drawings, and to the letters of reference marked thereon.

The nature of my invention consists in the construction of a double-pointed or bow-fork, the points of which are provided with cutting-edges, and the fork so constructed that arms thereon may be turned inwards, by means of a lever pivoted on the fork.

To enable others skilled in the art to make and use my invention, I will proceed to describe its construction and operation.

In the annexed drawings, forming part of this specification—

A represents a two-pronged hay-fork, with a handle, B, in the top of which is a ring, C, through which the rope to raise or lower the same is passed.

On the side of the prongs of the fork, arms D D are pivoted, and connected by means of the connecting-bars F F, at their upper end, to the lever E, which is pivoted to the fork below the handle B.

The connecting-bars are attached to the lever, one at its end, and the other to a point at the other side of the pivot, so that when the lever is raised or lowered, the connecting-bars move in opposite directions, thereby moving the arms D D either inward or outward at the same time.

The points of the fork are cut with a square notch, α , on the outer edge, and the points of the arms are cut with a similar notch, C, on their inner edge; the points below the notches being sharpened on both edges to make a cutting-edge for the purpose of penetrating the hay easily.

The handle B is provided with a pin, c, against which the lever E rests when raised, and when in that position the arms D D extend along the prongs of the forks. When the lever is lowered, the points of the arms are pressed inward, and the notches α and C C serve to hold the hay, so that it will not fall off.

What I claim as an improvement upon my patent for a hay-fork, dated April 9, 1867, is—

The arrangement of the bars A A and their points α α , bars D D pivoted as shown, and with points β β , connecting-bars F F, and lever E, all constructed and operating as set forth.

In testimony that I claim the foregoing, I have hereunto set my hand, this 9th day of May, 1868.

G. W. HEATH.
